UNITED STATES PATENT OFFICE.

ALBERT A. MERRILL, OF LOS ANGELES, CALIFORNIA.

STAGGERED CONVERGENT BIPLANE.

1,355,990.

Specification of Letters Patent.

Patented Oct. 19, 1920.

Application filed May 31, 1916. Serial No. 100,954.

To all whom it may concern:

Be it known that I, ALBERT A. MERRILL, a citizen of the United States, residing at Los Angeles, in the county of Los Angeles, 5 State of California, have invented new and useful Improvements in Staggered Convergent Biplanes, of which the following is a specification.

This invention relates to aeroplanes, and 10 the general object of this invention is to provide a machine more nearly inherently stable than machines heretofore constructed, and to provide a machine in which vertical control may be and is effected without the 15 use of an elevator.

I can best explain the general nature of my invention by referring first to the common mono-plane type of machine. Such a machine in reality comprises two planes, a 20 large supporting plane and a small following plane at some distance behind the supporting plane at the rear end of the framework. The elevator usually follows immediately behind this following plane. At ordinary speeds of flight the time elapsing 25 between the entry of the forward supporting plane into disturbed air and the time when the following plane enters said air is sufficient to allow the machine to oscillate about its lateral axis before the instant 30 when the following plane enters said air and when the balance of the forces is restored. The fact that such oscillations of the machine can and do take place under such circumstances makes it necessary to 35 use an elevator to overcome or counter-balance the turning moment of oscillation as quickly as possible. And, even with the best constructed machines, accidents are liable to occur due to the comparatively large 40 time period between the instant when the supporting plane enters the disturbed air and the instant when the following plane enters said air.

I reduce this time period to a practically negligible quantity by placing the following plane closely behind the supporting plane; that is, generally speaking, by decreasing the horizontal distance between the two 45 planes. The reducing of this distance of course makes it necessary to increase the size of the following plane in order that that plane may still have the same righting moment as before about the center of gravity of the machine. I make the horizontal 50 distance between the planes so small that,

under all ordinary circumstances, and at any of the usual speeds of flight, the time element above referred to is so short that the inertia of the machine about its lateral axis 60 cannot be overcome in that time period by any ordinarily encountered force, sufficiently to sensibly rotate the whole machine about the lateral axis. This being the case, the necessity of the elevator is 65 done away with; and I provide means for guiding the machine vertically by making a relative longitudinal shift between the center of gravity and center of support. I preferably make this shift by shifting the 70 center of gravity. I shift the center of gravity by the expedient of shifting a weight longitudinally in the machine; and this weight may be the whole power plant and the pilot, or any other weight. 75

My invention will be best understood from the following specification taken with reference to the drawings, in which specification and drawings I illustrate a preferred form of machine embodying my said 80 invention. In these drawings Figure 1 is a side elevation of a machine embodying my invention, Fig. 2 is a plan of the same, parts being broken away for purposes of illustration, Fig. 3 is a front elevation taken 85 as indicated by line 3-3 on Fig. 1, Fig. 4 is an enlarged detail section taken as indicated by line 4-4 on Fig. 3, Fig. 5 is a further enlarged detail section taken as indicated by line 5-5 on Fig. 4, and Fig. 6 90 is a diagram illustrating certain principles of my invention.

I shall refer first particularly to Fig. 6. Therein I show a forward supporting plane 10 and a following plane 11 arranged aft 95 and preferably beneath the supporting plane; and I show at 12 the usual position of the following plane on a monoplane. The distance denoted L is approximately the leverage distance between the plane 12 and the 100 center of gravity of the machine, while the distance denoted L' is approximately the leverage distance between the plane 11 and the center of gravity. In the diagram it will be noted that the plane 11 (the plane 105 of least inclination) is placed behind the plane 10 by a distance equal to about one half of the width of the plane 10. The righting moment of the plane 12 about the center of gravity of a mono-plane is measured by the product of the force exerted upon the plane 12 and its distance L from 110

the center of gravity. When I move the plane 12, so to speak, from its usual position at 12 to the position at 11 the lever arm is greatly lessened, as indicated at L', and 5 the force must be consequently augmented in order to obtain the same righting moment. This is done by increasing the size of the plane, so that the plane 11 is preferably identical in size and shape with the plane 10; but is placed at a slighter angle of 10 inclination than that of the plane 10. For instance, in a typical construction, I place the planes 10 and 11 in the relative positions shown, placing the chord of the plane 10 at 15 an inclination of about seven degrees and the chord of the plane 11 at an inclination of about four degrees, the two planes having a rearward convergence of about three degrees. It should be noted that the essential 20 feature of this disposition is that one surface is placed behind the other, and that the rear surface has the lesser inclination; but it is immaterial whether the rear surface is below or above the front surface. 25 When the rear surface is above the convergence is forward. In either case the moment of the righting couple is the same. The horizontal distance between the planes 10 and 11 is approximately half the width 30 of the planes, or with a chord of 6 feet this distance is 3 feet; and the time element hereinbefore referred to corresponding to this linear distance of 3 feet, and for a speed of say 60 miles per hour, is 1/29th of a second. This time element is too small to allow 35 of any oscillation of the whole machine about its lateral axis.

I now refer particularly to Figs. 1 to 5. I show the two planes 10 and 11 placed in 40 the relative positions hereinbefore explained, the planes being framed with struts 13 and brace wires 14 in the usual manner. The machine is provided with any suitable starting and landing apparatus such as is shown 45 at 16; and a rearwardly extending framework 17 is provided for carrying the vertical rudder 18 for steering. The planes 10 and 11 are provided at each end of the rear edge with the ailerons 20 and 21. The 50 ailerons at each end are connected by struts 22, whose connection to the ailerons may be pivotal in any of the well known manners, and all of the ailerons are made to act cooperatively by a suitable connecting means, 55 preferably a connecting wire 23 which connects to each of the upper ailerons and passes downwardly and over pulleys 19 and across the bottom part of the machine. Control of the ailerons is preferably by means 60 of a wheel 24 located in front pilot seat 25. Wires 26 wind around a drum or spool 27 operated by the wheel 24, and these wires 26 extend outwardly and upwardly and over pulleys 28 beneath the upper plane 10 and 65 thence downwardly to connect with the

lower ailerons 20. Control of the rudder 18 is had through the medium of wires 30 which connect to a foot lever 31 and extend outwardly to pulleys 32 near the outer ends of the lower plane 11 and thence extend to the 70 rudder 18.

The motor 40, with the propeller 41, and controls 24 and 31, and pilot seat 25 are all mounted upon a sliding base. This sliding base 45 is mounted in suitable ways 46 between suitably constructed beams 47; the beams and ways being so placed that the sliding base is arranged parallel to the longitudinal axis of the whole machine. I have hereinbefore stated that in order to 80 shift the center of gravity of the machine I prefer to shift the weight longitudinally; and in the form of mechanism herein described the weight to be shifted includes the power plant, the controls and the pilot, all 85 of which are carried on the sliding base 45. In the normal position of the sliding base and the parts carried thereon, the center of gravity of the whole machine is at such a point that the machine will fly at a predetermined angle of incidence; and provision is made for moving the sliding base and the parts carried thereon either forward or back of the normal medial position so as to materially shift the center of gravity either 95 forwardly or rearwardly. Shifting the center of gravity with reference to the center of support immediately changes the angle of incidence and causes the machine to climb or glide, as may be desired. 100

I prefer to move the sliding base longitudinally by means of a hand lever 50 mounted upon a transverse shaft 51, extending across the sliding base 45 and carrying near its center a drum 52. A cable 53 winds around 105 the drum in the manner indicated and the ends of the cable are secured to the cross pieces 54 which connect to and space the beams 47. A toothed sector 55 is provided for the lever 50, and a dog 56, entering the 110 sector notches, holds the lever in any set position; and consequently holds the sliding base 45 in any set position with reference to the ways 47 and 46.

It will be understood that, by arranging 115 the following plane closely behind the supporting plane, I provide that the machine shall not oscillate about the lateral axis upon entering disturbed air conditions. Consequently the only vertical control necessary is that needed for guiding the machine up and down; and, in the specific preferred form described, this is provided by shifting the center of gravity of the machine. It will be noted that I place a considerable portion of the complete weight of the machine upon the sliding base 45; so that a movement of the sliding base causes a relatively considerable movement of the center of gravity of the whole machine. In 125 130

such circumstances it is not necessary to move the sliding base a great distance either ahead or behind of its normal medial position for extreme control of the machine; 5 and it will be noted that these movements do not affect the control wires 26 and 30 as those control wires normally extend transversely outwardly to the outer ends of the planes 10 and 11, and normally extend 10 at right angles to the line of movement of the sliding base; so that a very slight resilient extension of the wires is sufficient to allow the forward and back movement of the sliding base.

15 Having described a preferred form of my invention, I claim:

1. In a flying machine, supporting surfaces embodying exclusively a plurality of supporting planes spaced one above the 20 other and slightly in front of the other, the chords of said surfaces being convergent, and the angle of incidence of the front surface being greater than that of the rear surface, the horizontal spacing of said planes 25 being relatively small, and means for longitudinally shifting the center of gravity of the machine as a whole, said last mentioned means being the sole vertical steering means.

30 2. In a flying machine, supporting surfaces embodying exclusively a plurality of supporting planes spaced one above the other and one slightly in front of the other, the chords of said surfaces being convergent, and the angle of incidence of the front surface being greater than that of the rear surface, the horizontal spacing of said planes 35 being relatively small, and means for vertically steering the machine embodying exclusively means for making a relative longitudinal shift between the center of gravity and the center of support of the machine.

3. In a flying machine, supporting surfaces embodying exclusively a plurality of 45 supporting planes spaced one above the other and one in front of the other, the chords of said surfaces being convergent and the angle of incidence of the front surface being greater than that of the rear surfaces, the horizontal spacing of said planes 50 being relatively small, and a single means for vertically steering the machine, said means operating by longitudinally shifting the position of the center of gravity of the 55 machine as a whole, and embodying a weight and means for shifting said weight longitudinally of the machine.

4. In a flying machine, supporting surfaces embodying exclusively a plurality of 60 supporting planes spaced one above the other and one in front of the other, the chords of said surfaces being convergent and the angle of incidence of the front surface being greater than that of the rear surface, the horizontal spacing of said planes 65 being relatively small, and a single means for vertically steering the machine, said means operating by longitudinally shifting the position of the center of gravity of the 70 machine as a whole, and embodying a longitudinally movable frame mounted upon the machine, power plane and propulsion means mounted upon said longitudinally 75 movable frame, controls mounted upon said longitudinally movable frame, and means under control of the pilot for moving and setting said frame.

In witness that I claim the foregoing I have hereunto subscribed my name this 23d 80 day of May, 1916.

ALBERT A. MERRILL.
